UNITED STATES PATENT OFFICE

169,631

INFLATABLE FLOAT

William Z. Norman, New York, and Julius Billig,
Kew Gardens, N. Y., assignors to Bilnor Corp.,
Maspeth, N. Y., a corporation of New York

Application July 11, 1950, Serial No. 11,069

Term of patent 3½ years

(Cl. D34—15)

To all whom it may concern:

Be it known that we, Julius Billig and William Z. Norman, citizens of the United States and residents respectively of Kew Gardens, county of Queens, and New York, county of New York, and State of New York, have invented a new, original, and ornamental Design for an Inflatable Float, of which the following is a specification, reference being had to the accompanying drawing, forming part thereof.

In the drawing:

Figure 1 is a perspective view of an inflatable float, embodying our design; and

Figure 2 is an edge elevational view of this inflatable float.

We claim:

The ornamental design for an inflatable float, as shown.

WILLIAM Z. NORMAN.
JULIUS BILLIG.
